ROBERT HITCHCOCK, OF SPRINGFIELD, MASSACHUSETTS, ASSIGNOR TO
JOHN MULLIGAN AND JOHN H. HARE, OF THE SAME PLACE.

Letters Patent No. 64,316, dated April 30, 1867.

IMPROVED GUIDE FOR AXLE-BOXES.

The Schedule referred to in these Letters Patent and making part of the same.

TO ALL WHOM IT MAY CONCERN:

Be it known that I, ROBERT L. HITCHCOCK, of Springfield, Hampden county, Massachusetts, have invented a new and improved Guide for Axle-Boxes; and I do hereby declare that the following is a full, clear, and exact description thereof, reference being had to the accompanying drawings making part of this specification.

The object of this invention is to obviate the difficulty hitherto existing in the arrangement of the "jaws" on railroad trucks or cars, which consisted in the use of fixed guides for the axle-box, so that when the said guides were worn off the whole jaw had to be thrown away. My invention overcomes this objection by arranging detachable guides, which are secured to the "jaw" by bolts or other means, and which when worn out can be easily renewed. I want it to be understood that this invention is not applicable to locomotives, but only to the cars and trucks on railroads. In the annexed drawing my invention is completely illustrated—

Figure 1 being a front elevation of the jaw and axle-box.

Figure 2 is a vertical cross-section through the jaw, taken on the line $x-x$, fig. 1.

Figure 3 is a horizontal sectional view of the same, taken on the line $y-y$, fig. 1.

Figure 4 is an inside view of one of the detachable guides.

Similar letters indicate like parts.

A is the jaw, made of cast iron or other suitable material in the ordinary manner, with the exception of the guide pieces, which herein are made independent from the jaw. They are metal plates, which are secured to the inner surface of the jaws by means of bolts and nuts $a a$. For further security the guides are provided with a wedge-shaped projection, b , (fig. 4,) fitting into a wedge-shaped recess, c , (fig. 2,) in the jaw. The heads of the bolts $a a$ are countersunk in the plates B B, and the plates are provided with guide flanges or bars, $d d$, in the same manner as they were usually arranged formerly in the jaws. It will thus be seen that by this arrangement the jaw itself is protected and will not have to be removed as frequently as has now been done.

Having thus described my invention, what I claim, and desire to secure by Letters Patent, is—

The detachable metallic guide plates B B, provided with flanges $d d$ upon their inner edges, and having the wedge-shaped projections b fitting into the wedge-shaped grooves in the jaws A, when all are constructed and arranged as herein set forth for the purpose specified.

ROBT. HITCHCOCK.
